UNITED STATES PATENT OFFICE.

DARIUS C. NEWELL, OF YONKERS, NEW YORK.

IMPROVEMENT IN MACHINES FOR SEPARATING WASTE FROM SAWDUST.

Specification forming part of Letters Patent No. 177,268, dated May 9, 1876; application filed January 18, 1876.

To all whom it may concern:

Be it known that I, DARIUS C. NEWELL, of Yonkers, in the county of Westchester and State of New York, have invented a Machine for Separating Chips, of which the following is a specification:

In planing and molding mills, and other similar machines for working wood, the refuse chips are usually burned under the boilers of the mill, for the reason that they can be applied to no more useful purpose, although they include the finer matter analogous to sawdust, which may be put to a more valuable use.

The object of my invention is to separate the fine chips from the larger; and it is accomplished by running the chips, as they come from the machine, over a sieve or screen placed in the slide or chute through which they are carried to the fire-room. In their passage over the screen the fine portions of the chips, the size of which is regulated by the size of the meshes of the screen, are separated by falling through the meshes, while the larger portions are transmitted by the carrier-chain along the slide. The screen has a short, quick motion of its own, imparted as if by a blow, which prevents the choking of its meshes. The chain may be kept tight by any of the means usually employed in similar cases for that purpose.

To enable others skilled in the arts to which it appertains to make and use my invention, I will proceed to describe its construction and operation, with reference to the drawing.

Figure 1 is a sectional elevation of the machine as applied to a horizontal slide, and Fig. 2 is a plan of the same.

The carrier-chain *a* is provided with the cross-bars *b*, and is put in motion by the ro-

tation of the drum *c*, which may be driven by a belt on the pulley *d*. The machine has a similar drum at the other end. The screen *e* is mounted on a frame, which is carried on the vibrating levers *f*, and receives its motion through the rod *g* from the rotation of a cam with three spurs on the shaft *h*, which has a pulley, *i*, at one end, and is driven by a belt from the pulley *k* on the main drum of the machine. The strips *l* cover the open joints between the frame of the slide and that of the screen.

The novelty and usefulness of my invention consist in the separation from the general mass of the chips, resulting from the use of wood-working machinery, of those finer particles which are the more valuable; and, while I do not claim the use of a sieve for the separation of small matter from the larger, with which it is intermixed, my improvement consists in the treatment of refuse chips by a process involving the use of a sieve, by which a portion of them is separated for a more valuable purpose.

It may be used in connection with a planing-mill, or a molding-machine, or a grinding-machine, or any other wood-working machinery.

I claim as my invention and desire to secure by Letters Patent—

The combination, in a carrier for chips from wood-working machinery, of the screen *e*, vibrating levers *f*, the cam on the shaft *h*, the chain *a*, and the cross-bars *b*, constructed, arranged, and operated substantially as described, and for the purpose specified.

DARIUS C. NEWELL.
